UNITED STATES PATENT OFFICE.

DAVIS BARNARD, OF LOS ANGELES, CALIFORNIA, ASSIGNOR TO BARNARD LIGHT AND HEAT COMPANY, OF LOS ANGELES, CALIFORNIA, A CORPORATION OF CALIFORNIA.

ACETYLENE-GENERATOR.

No. 851,613.

Specification of Letters Patent.

Patented April 23, 1907.

Application filed May 15, 1905. Serial No. 260,381.

To all whom it may concern:

Be it known that I, DAVIS BARNARD, a citizen of the United States, residing at Los Angeles, in the county of Los Angeles and State of California, have invented a new and useful Improvement in Acetylene-Generators, of which the following is a specification.

This invention relates to the class of acetylene generators, wherein carbid is charged into the generating tank intermittently to produce the gas in accordance with the demands on the machine.

An object of the invention is to provide a machine that is unitary in form and construction, the containing parts for the generator and gas holder forming a compact substantially unyielding body, thereby avoiding considerable work and trouble in setting up the machine, and also avoiding risk of relative displacement of the parts after setting up, by settling of the supports, such as is liable to occur with generators wherein the generating and gas holder tanks are separate.

Another object of the invention is to provide a generator of extreme compactness and minimum size for a given capacity, and of convenient shape for packing, transportation and use.

Another object of the invention is to enable the generator to be thoroughly cleaned by flushing out without substantially changing the water level therein or admission of air thereto. To attain this result, means are provided for effectively agitating the material in the generator tank throughout the bottom portion thereof, so as to bring all the solid matter therein into suspension in the water.

A further object of the invention is to insure that the carbid when charged into the generator tank will be brought into effective contact with the liquid, this being effected by an automatic agitator.

Another object of the invention is to provide a generator which will work effectively and safely under widely varying temperatures.

An important feature of the invention in connection with all the above mentioned objects, is that the generator is constructed in substantially rectangular form, the gas holder and generator tanks being formed as adjacent parts of a rectangular casing, this

construction giving the unity and compactness above referred to, and also enabling effective operation of the agitating means for stirring the sediment of lime and for forcing the carbid into contact with the liquid.

A further object of the invention is to provide for accurately measuring the charge, and for positive full charging movement at each operation without possibility of sticking or partial operation.

The accompanying drawing illustrates the invention.

Figure 1 is a side elevation of the machine. Fig. 2 is a longitudinal vertical section thereof. Fig. 3 is a vertical section on the line X^3-X^3 , Fig. 2. Fig. 4 is a vertical section of the carbid receptacle and feeding means, on the line X^4-X^4 , Fig. 2. Fig. 5 is a section on line X^5-X^5 , Fig. 1, showing the operative means for the carbid feed. Fig. 6 is a vertical section of the valve or plunger member for the carbid feed on the line X^6-X^6 , Fig. 7. Fig. 7 is a horizontal section of said plunger member on line X^7-X^7 , Fig. 6. Fig. 8 is a perspective of the sediment agitator. Fig. 9 is a vertical section showing a modified form of the carbid feed. Fig. 10 is a diagrammatic plan of another embodiment of the invention. Fig. 11 is a section on line $X^{11}-X^{11}$, Fig. 1.

1 designates the case or containing means consisting of a rectangular shell formed for example of sheet metal, said shell being of sufficient size to serve as a containing tank both for the generator proper and for the gas holder. Said shell may have stiffening ribs 1' extending around the same. A partition 2 extends vertically in said shell separating the generator portion or tank 3 from the gas holder portion or tank 4 thereof. Said generator tank 3 is closed at top and the gas holder tank 4 is open at the top to form a well in which the gasometer bell or gas holder 5 is contained, said gas holder moving vertically within said well, space or chamber and being guided by lugs 3' thereon, working on suitable frame 6.

7 designates the water supply pipe or connection leading to the generator chamber or tank 3, provided with a suitable valve indicated at 8.

9 designates the combined drainage overflow pipe and flushing outlet which is con-

nected to the tank or chamber 3 by means of a riser 10 formed as a rectangular extension on one end of the case 1, and communicating at its lower end with the chamber 3, the pipe 5 9 leading from the side of said riser at the height or level at which it is desired the water shall stand in the riser, it being understood that this level will be somewhat higher than the level in the generator tank, due to 10 pressure of the gas in the latter. The riser 10 is open at the top. 11 designates a riser formed at the other end of the rectangular casing 1, said riser being also preferably formed as a rectangular extension on the end 15 of the casing, and pipe 12 extends upwardly from the lower part of the riser 11 to above the level of the water within the gasometer bell 5, said pipe opening at its upper end into the space within the bell so as to carry the 20 gas therein down into the lower end of the riser 11, in which the gas rises through a suitable filtering or scrubbing material 13 to an outlet 14, from which the usual connection is made to the burners.

25 The pipe 15 extends from the space within the gasometer bell downwardly to the lower part of the generator and is connected through the partition 2 to the pipe 16 leading upwardly and communicating at its upper 30 end with the space above the water level in the generator tank or chamber 3.

35 17 designates the carbid receptacle or casing preferably formed as an upward extension from the top of casing 1, a funnel or inclined floor 18 being provided therein to cause the carbid to gravitate toward a discharge aperture 18; this funnel is preferably somewhat above the casing 1, so as to leave a space below said funnel and within the extension 17, the pipes 16 extending upwardly into this space above the outlet of the carbid feeding means.

40 19 designates the charging hole for the carbid chamber 17, said hole being closed when the machine is in operation by screw plug 19'.

45 The carbid feeding means comprises a tube 20 preferably rectangular in shape and extending horizontally below the funnel 18, being attached to and carried by said funnel 50 and communicating therewith. A plunger member 21 sliding in said top reciprocates below the discharge outlet 18 to the funnel to feed the carbid toward the discharge end of the tube by definite amounts. This reciprocating movement is effected by the arm 55 22 on rock shaft 23 extending through the well of the carbid casing 17, said arm being connected to said plunger member by a link or rod 24 pivoted to the plunger member and 60 to arm 22. Arm 22 also acts as a door or closure for the end of tube 20, to exclude moisture from the carbid when the latter is not being fed. Rock shaft 23 extends through a side wall of the carbid casing 17 65 and is connected exteriorly of the casing

with means for operation thereof, to feed the carbid from time to time. Said operating means is controlled by the gas-holder and is operated preferably through a connection which will give positive or full operation of the feed under all circumstances. For this purpose, shaft 23 may be provided with an overbalancing or double throw device, which may be any suitable construction, operated by weight or otherwise, to tend to move to either side from a central position. Said device may for example, consist of a weight-carrying tube 26 containing balls 27, which as the tube is inclined one way or the other, tend to roll toward the lower end of the tube and by their weight tend to force the lower end of the tube still farther down. Said tube is closed at each end to retain the balls therein. An arm 28, rigidly connected with the tube 26 carries a latch 29 pivotally connected thereto, and adapted to be engaged by a stud or projection 30 extending from the gas holder, the latch 29 hanging in the path of said projection in such manner that as the gasometer rises, it will engage under said latch which is provided with stop means limiting its upward movement relative to the arm 28, so that the continued upward movement of the gas holder will cause the tubular overbalancing device or lever 26 to tip to the left of the horizontal plane as shown in Fig. 3, whereupon the balls 27 will roll to the left end thereof and forcibly complete this tipping motion of the tube of the balance device. This movement shifts the plunger 21 aforesaid, to the position shown in Fig. 4 and causes closure member 22 to bear against the end of the feed tube 20. On the downward movement of the gas holder, the stud or projection 30 strikes and depresses the tubular overbalancing device 26 and presses the tube to overturn the same, causing the balls therein to fall toward the other end. This movement brings the carbid feed-plunger 21 to the position shown in dotted lines in Fig. 4, causing expulsion of a definite amount of the carbid from the tube 20. In either case, the completion of the movement of the carbid-feed is not dependent on the completion of the movement of the gas-holder, the latter only having to tip or overturn the overbalancing device which itself completes the movement. Arm 28 is preferably provided with an extension 31 reaching upwardly therefrom to form a guard for maintaining proper engaging relation between the projection 30 and the overbalancing means; said projection 30 is preferably adjusted on the gasometer-bell as by means of a set screw device 30'.

125 The operating means for the carbid-feed is preferably provided with a lost-motion connection, permitting the initial movement of the overbalancing device, previous to its reaching the "dead center" or overbalancing 130

point; said means may comprise a forked arm 55, rigidly connected to tube 26 by set screw 62 and an arm 57 rigidly connected to shaft 23, and playing between a lug 58 on arm 55 and a screw 59 on a lug 60 on arm 55, tube 26 being rotatably mounted on shaft 23, and carried by a stud shaft 23'. The above-described connection gives a lost motion between said shaft and tube, and the extent of the lost motion can be adjusted by screw 59, and the position of arms 55, 57, can be adjusted by set screws 62, 63.

41, 41', designate taps for drawing off condensation from the pipe 15 and purifier 11.

15 The plunger 21 is shown as an inverted U-shaped member having closed walls 32, 32', at front and back, and open at each side and bottom, and an inverted V-shaped rail 33 extending longitudinally at the bottom 20 slightly below the level of ends 32, 32', so as to form a bearing face for the plunger. The edges of ends 32, 32', are beveled and rear end 32' is notched, all of these features being 25 for the purpose of clearing the plunger of carbid and allowing it to move freely. 54 designates a stop on the plunger.

The generator is cleaned out by flushing out all of the material therein through aforesaid outlet 9, and for this purpose it is necessary to bring the solid material or sediment 30 into suspension. This is effected by agitator 34 formed as a rectangular open-work frame of substantially the full width of the generator-tank 3, and having projections 35 extending upward therefrom, this agitator reciprocating endwise of the tank so that substantially every portion of the bottom of the tank will be subjected to the stirring action thereof. This agitator is preferably operated by means extending upwardly through 40 the riser 10, this being a convenient means of extending the operating device to the outside of the machine, and also having the advantage that this operating means of itself 45 serves as an agitator for the material within the riser. Said operating means may consist of a lever 36 pivoted at 37 in the riser and pivoted at its lower end to the agitator 34, said lever being provided at its upper end 50 with a handle 38 for manual operation. A cover or lid 39 is preferably provided for the riser 10, said lid having a perforation 40 to fit over the handle 38 when the lid is put in place, it being understood that said lid is removed when the agitator is to be operated. The riser 10 communicates with the generator-tank solely near the bottom of said tank 55 so that when the water in said tank is agitated only the roily bottom portion thereof finds its way into the riser to be discharged therethrough. Since the lever 36 extends through the riser, the movement of said lever keeps the water agitated while it is passing through the riser, so that sediment will 60 not collect at the bottom thereof.

In machines of this type it is found that the carbid sometimes has a tendency to accumulate on the surface of the liquid, particularly when the machine has been running such a length of time that the liquid becomes 70 thick or pasty, due to the accumulation of solid matter therein, the downward movement of the carbid into the liquid being resisted by the thickness of the liquid and by the floatative effect of the gas entangled within the carbid. The carbid thus resting on the top of the liquid or partly submerged therein, operates in an unsatisfactory manner in the generation of the gas, the action being local or concentrated and not in immediate proximity to a large mass of water, whereas the conditions for safe and efficient generation are that the action should be distributed over as large a surface as possible and throughout as large a mass of water as 80 possible so as to keep down the heat generated by the action and expose all parts of the carbid to the action of the liquid. To overcome this difficulty, I provide an agitating, stirring or mixing device that acts on the 85 carbid falling in the generator tank, to force the same downwardly into the liquid. Said stirring or depressing device is preferably in the nature of a paddle wheel, comprising radial arms, frames or stirring members 42 mounted on a shaft 43, which extends through the side wall of tank 3 for connection with the operating means herein-after described. Such arms or frames 42 may carry ribs 44 formed for example of 90 wire netting or other foraminous material. This stirring device is preferably operated automatically by connection with the gas holder, the shaft 43 carrying for example a toothed wheel 45 engaged by a pawl 46 on 95 an arm 47 pivotally mounted on said shaft and connected by a link or rod 48 with one of the guide lugs 3' of the gas holder, so that on each downward movement of the gas holder, the pawl 46 engages tooth wheel 47 to cause 100 partial rotation of the stirring paddle wheel device 41. On the upward movement of the gas holder, the pawl will slip idly over the tooth wheel.

A compact and efficient construction is afforded by reason of the shaft 23 which is actuated by means including the vibrating operating arm 28, being fixed directly to and forming a hinge for closure 22, and said closure 22 being connected by a single link 24 to the plunger 21, so that closure 22 forms a pivoted arm adapted to transmit power from the operating means to the feed device.

The operation of the machine is as follows: Receptacle 17 is charged with carbid indicated at 50 and the generator tank 3 is charged with water which is allowed to run in until it overflows at the outlet 9. The carbid feed is operated manually or otherwise to feed sufficient carbid into the gen- 125 130

erator to start the machine, the gas generated therefrom passing through pipes 16 and 15, into the gas holder and raising the latter, the operation then proceeding automatically in the following manner: As the gas holder rises, the projection 30 thereon operates the tubular balancing device 26 as above described, moving the plunger 21 to position shown in full lines in Fig. 4, closing the carbid tube 20 at 22 and allowing carbid to run into the tube from the funnel above the same. Assuming that the gas is being used, the gas holder will gradually descend bringing the stud 30 thereon against the overbalancing device 26 as above described to cause operation of the latter, thereby causing the plunger 21 and closer 22 to move to the position shown in dotted lines in Fig. 4. This operation shoves a definite measured amount of the carbid out of the open end of the tube. This carbid falling into the water in the generator tank causes further generation of gas with the result that the gas holder again rises, this operation being continued indefinitely as long as the carbid supply lasts. Each time that the gas holder rises, it overcomes the weight of the balls 27, which at that time are at the longer end of the tube and thereby stores energy due to the lifting of the balls. When the tube is thus brought to a position a little beyond the horizontal, the balls run to the other end. This is a short end and only gives the balls sufficient leverage to complete the upward tilting of the tube, but on the downward movement of the gas holder, the moment the tube overbalances and the balls run to the lower end, a strong leverage will be brought to bear on the rock shaft 23 to cause effectual movement of the carbid feed. The lost motion in the connection between the rock shaft and the carbid feed permits the initial movement of the rock shaft 23, while the tube is approaching the overbalancing point, without interference therewith due to the friction of the feed, and then when the connection is made, the pressure is brought thereon suddenly and with full force, so as to insure full operation. Sticking of the feed at partial cut off and dribbling of the carbid into the tank are thus prevented. At each descent of the gas holder, the rod 48 and lever 47 operate through the pawl 46 to turn the wheel 45 and shaft 43 to give partial rotation to the automatic stirring device, thereby forcibly depressing or stirring the carbid into the body or mass of liquid and giving more effectual and safer generation as above set forth. Owing to this forcible automatic mixture of the carbid with the liquid, the capacity of the machine for a given size is thereby largely increased, as it is possible to use a given quantity of liquid longer than 65 is possible in the usual machine, wherein

thickening of the liquid interferes with the contact of the carbid with the water as above explained. It will be necessary, however, from time to time, to clean out the generator tank and an important feature of the invention is that this may be accomplished without substantial disturbance of the water level therein or admission of any air to the generator.

It is customary to drain off the waste matter and sediment by opening a drainage outlet at the bottom, allowing the water, accumulated lime, etc., to run off, and at the same time admitting air to prevent suction within the tank. This admission of air is a source of inconvenience in that it interferes with the proper operation of the plant for a considerable time thereafter, the air injuriously diluting the gas. In cleaning the machine above described, it is only necessary to turn on the supply of water to the generator and, removing lid 39, vibrate the handle 38 to cause the agitator 34 to reciprocate at the bottom of generator tank, thereby bringing all of the accumulated solid matter into suspension and enabling same to be flushed out along with the water, without disturbing the water level or requiring admission of any air.

The construction of the machine may be variously modified without departing from the invention. For example, instead of a reciprocating plunger for the carbid feed, the vibrating feed device, indicated at 51, in Fig. 9, may be used, the same being pivoted to tube 20' at 52 and connected by the link 24 to the operating arm and closure 22' as above described, for the plunger 21. A flap or trap door 53 may be pivoted at the rear end of the feed tube 20'.

A plurality of generator tanks may be formed in a single rectangular casing, together with a single gas holder tank operating in common therewith. Such a construction is shown in Fig. 10, wherein 3^a, 3^b designates two generator tanks connected by piping 16^a, 16^b, with a gas holder tank 4^a, the construction being shown only diagrammatically and the details being substantially as above explained.

The rectangular shape of the casing is of especial advantage in enabling the generator and gas holder tanks to be brought into immediate proximity with only an intervening partition, with the result that heat is readily transmitted from either of said tanks to the other, consequently the overheating of the liquid in the generator tank by the chemical reaction is prevented by the cooling effect of the adjacent body of water in the gas holder tank; and conversely, freezing or excessive cooling of the water in the gas holder tank in cold weather is prevented by the moderating or warming effect of the water in the generator tank, particularly on account of the heat-

ing of such water by the chemical action therein. Further advantages of the rectangular form may be mentioned as follows:— strength and compactness of form; uniformity of pressure of gas; concealment and enclosure of all pipes so that atmospheric changes in temperature, etc., will not cause condensation or change of the gas, and leaks or displacement in shipment will be avoided; 5 enabling effective operation of the manual and automatic agitators as above described, and cleaning of the generator without change of water level; conserving an even temperature of the water in both tanks, and providing greater water surface than any other form of generator. The purifier through which the gas passes from the gas holder to the point of consumption being formed as an extension on the side of this rectangular casing 15 and of dimensions proportionate to the dimension of the generator, it follows that it will be properly proportioned in its action to the size of the machine and effective purification will be insured for all sizes of machine. 20 25 The rectangular carbide holder has the advantage that bridging therein is not so liable to occur as in the round holder, and the nature of the carbide feed further reduces the risk of bridging as it leaves a large, free opening at 30 the bottom of the rectangular funnel or inclined floor of the holder into which the carbide can freely fall.

What I claim is:—

1. In an acetylene generator, a feed device comprising a horizontal feed tube, a plunger reciprocating therein, a funnel communicating with the upper side of said tube, and a pivoted arm connected to transmit power through said operating means to said feed device and formed as a closure for the end of the tube, a shaft to which said arm is fixed and means for rocking said shaft.
2. In an acetylene generator, a feed device comprising a funnel, a feed tube, a plunger reciprocating therein, a rock shaft, a closure for the tube fixed on said shaft, a link connecting said plunger and closure, and a lever fastened to said shaft to rock the same.

3. In an acetylene generator, a feed device comprising a funnel, a feed tube, a plunger reciprocating therein, a rock shaft, a closure for the tube fixed on said shaft, a link connecting said plunger and closure, means for rocking said shaft, and overbalancing operating means mounted on said shaft and provided with a weight shiftable automatically from one side to the other of the shaft. 50 55

4. In an acetylene generator, a feed device comprising a funnel, a feed tube, a plunger reciprocating therein, a rock shaft, a closure for the tube fixed on said shaft, a link connecting said plunger and closure, means for rocking said shaft, and overbalancing operating means mounted on said shaft and provided with a weight-carrier and a weight 60 65 shiftable automatically from one side to the other of the shaft, there being a lost-motion connection between said shaft and weight-carrier.

5. In an acetylene generator, a feed device comprising a feed tube and a plunger reciprocating therein, a vibrating operating arm, an overbalancing device connected therewith, and a lost motion connection between said operating arm and feed device, said vibrating 70 75 operating arm being provided with an adjusting device to adjust the extent of the lost motion.

6. In an acetylene generator, a feed device comprising a feed tube, a hopper communicating with one side thereof, a plunger reciprocating therein, a hinged closure for said tube swinging toward and from an end thereof, a link connecting said tube and plunger, a rock shaft forming the hinge for 80 85 said closure and fixed thereto, and means independently of the closure for rocking said shaft.

In testimony whereof, I have hereunto set my hand at Los Angeles, California, this 4th 90 day of May, 1905.

DAVIS BARNARD.

In presence of—

ARTHUR P. KNIGHT,
JULIA TOWNSEND.
